UNITED STATES PATENT OFFICE.

RAFFAELLO ASTARITA, OF NEW YORK, N. Y., ASSIGNOR TO SONDHEIM & MAGNUS, OF SAME PLACE.

DESIGN FOR A PILLOW-TOP.

SPECIFICATION forming part of Design No. 31,766, dated October 31, 1899.

Application filed October 5, 1899. Serial No. 732,730. Term of patent 3½ years.

To all whom it may concern:

Be it known that I, RAFFAELLO ASTARITA, a subject of the King of Italy, residing in the city of New York, borough of Manhattan, in 5 the county and State of New York, have invented and produced a new and original Design for a Pillow-Top, of which the following is a full, clear, and exact description.

Reference is to be had to the accompanying 10 drawing, forming a part of this specification, in which the figure is a face view of a pillow-top, showing my design.

The design in its entirety consists of a representation of two couples of dudishly-at- 15 tired persons seated on chairs and grouped around a table supporting a cake, bottle, and plates, a drinking-glass appearing in one hand of each person, a stool having canes and hats placed thereon appearing in the fore-

ground, the table, chairs, and stool appearing 20 resting on a tile flooring, and all within a border, the top of which border contains a scroll and open network above the heads of the persons, the whole representing the last phase of a cake-walk.

The leading feature of the design consists of the representation of couples of persons grouped around a table, the whole representing the last phase of a cake-walk.

Having thus described my invention, I 30 claim as new and desire to secure by Letters Patent—

The design for a pillow-top herein shown and described.

RAFFAELLO ASTARITA.
